SELECTING MECHANISM

Original Filed Feb. 23, 1927

UNITED STATES PATENT OFFICE

STERLING MORTON, OF CHICAGO, ILLINOIS, ASSIGNOR TO TELETYPE CORPORATION, OF CHICAGO, ILLINOIS

SELECTING MECHANISM

Application filed February 23, 1927, Serial No. 170,373. Renewed September 18, 1929.

The present invention relates to improvements in selecting mechanisms. More particularly the invention relates to improvements in selecting mechanisms, especially adapted for the operation of printing telegraph mechanisms.

A primary object of the invention is to provide a light compact arrangement of selecting and control mechanisms, adapted for printing telegraphs in which the number of parts involved is small, and the parts are adapted for economical manufacture.

Another object of the invention is to provide novel selecting and printing mechanisms for printing telegraphs adaptable for use either in tape or page printing mechanisms whereby the same parts may be utilized in the manufacture of both types of printers, reducing the manufacturing cost thereof.

Still another object of the invention is to provide a light weight selecting and printing mechanism which is adapted to be moved across a sheet of paper, eliminating the necessity for moving the paper for page printing, and also is adapted to be used as a stationary unit when it is desired to move the paper for spacing purposes.

A further object of the invention is to provide novel selecting mechanisms adapted for operation either by a single magnet or by a plurality of selector magnets.

Still a further object of the invention is to provide a mechanism in which the operation of the functions is entirely separated from the printing mechanisms whereby the functions may be operated by power mechanism independently of the printing mechanism, permitting the utilization of relatively small powers and light weight parts for the selecting and printing operations and substantially heavier powers and parts to operate the function or control mechanisms.

Further objects of the invention are such as will appear to one skilled in the art from the detailed description of the preferred embodiments hereinafter set forth, and as are defined by the terms of the appended claims.

As shown in the drawing, Figure 1 is a sectional side elevation show-

ing the essential parts of a preferred embodiment of my invention.

Figure 2 is a front elevation partially in section and with parts broken away and with parts removed of the form of invention shown in Figure 1.

Figure 3 is a detailed sectional view of the spacing worm and lifting bail cam utilized in the preferred form of invention.

Figure 4 is a fragmental sectional view taken along line IV—IV of Figure 2.

Figure 5 is a detailed side view of the striking arm utilized in the form of invention shown in Figure 1.

Figure 6 is a front view of the arm shown in Figure 5.

Type printing mechanisms being well known in the art, only so much of the well known mechanisms to be utilized in connection with the present invention will be described as will be essential to enable those skilled in the art to understand the present invention fully. In the preferred embodiment, my invention comprises setting vanes 1 to 5 inclusive which are provided at their ends with the vane pivots journaled in suitable bearings carried by a supporting frame of any suitable type (not shown). Vanes 1 to 5 are provided with the actuating extensions 7 (Figure 2) which are operated by control or vane setting members 8. The setting members 8 are operated by a mechanism, not shown, to tilt the vanes 1 to 5 about their pivots 6 to positions slightly inclined with the vertical, in accordance with code combinations of received marking or spacing conditions. Various mechanisms of a type suitable to actuate members 8 are well known in the art and form no part of the present invention. This mechanism may, for example, be of the multiple magnet type shown in U. S. patent to Pfannenstiehl #1,874,606 issued April 12, 1921, or may be of any well known single magnet type.

The upper edges of the vanes 1 to 5 inclusive fit slidably into notches formed in extensions 9 of character selecting or permutation disks 10 to 14 inclusive. The periphery of the disks 10 to 14 are notched so that the disks may be shifted in various com-

binations to selectively align the notches in a manner well known to those skilled in the art. Disks 10 to 14 inclusive are spaced apart and mounted for limited relative rotation on the supporting studs 15, preferably four in number which are secured at their lower ends to and carried by supporting casting or plate 16. Secured to and supported from the upper ends of studs 15 is the circular guide and spacing plate 18 which is provided with spaced radial guide slots 19 for selector latches 20. A latch 20 is provided for each selective operation to be performed under control of the disks 10 to 14. Latches 20 at their lower ends are pivotally supported on ring 21 and are spaced by projections 22 of the comb plate 23 upon which the pivot ring 21 is mounted. Secured to extensions 24 of latches 20 are the lower ends of helical springs 25 which at their upper ends are secured to pins 26 of guide plate 18. Springs 25 tend to urge latches 20 inward about their pivots into engagement with the peripheries of permutation disks 10 to 14 inclusive. Formed integrally with each of the latches 20 are the restoring projections 27 which extend over the circular edge of latch lifting plate 28, to which the type wheel stop 28' is secured for a purpose which will more fully herein appear. Plate 28 is guided for vertical reciprocation on studs 15 and secured to this plate by means of pin 29 is a lifting roller 30 which rides on the periphery of a lifting cam 31. Lifting cam 31 is formed integrally on a sleeve 32 which is slidably keyed to and movable on printer main shaft 33 and has formed integrally therewith a spacing worm 34. Shaft 33 is driven intermittently through a suitable single revolution clutch (not shown) from a continuously operating drive motor, the clutch being released in well known manner by the selecting mechanism upon the receipt of the last selecting condition of each code combination. Sleeve 32 together with the lifting cam 31 and spacing worm 34 are mounted between the bearing extensions 35 of plate 16, and shaft 33 is slidably journaled in the bearing extensions 35. Worm 34 meshes with teeth 36 of the spacing rack 37 which is supported on the outer ends of rack shifting arms 38. Rack shifting arms 38 are supported on shaft 39 which is pivotally supported on the main frame work of the mechanism (not shown). Secured in one of the arms 38 is a pin 40 to which the upper end of a spring 41 is secured. The lower end of the spring 41 is secured to the frame work in suitable manner and the spring 41 normally holds the teeth of rack 37 in engagement with the spacing worm 34. Pivottally secured to an extension of one of the arms 38 by means of a pin 42 is the end of a carriage return arm 43 which is operated as will more fully hereinafter appear to effect the carriage return.

Secured to the plate 16 by means of the cap screws 44 are the plates 23 and carriage frame casting 45. Formed integrally with frame 45 are the axially aligned bearings 46 and 47 for vertical shaft 48. Rigidly secured to the lower end of the shaft 48 is a type wheel stop arm 49 adapted to engage selected ones of latches 20 and the upper end of pin 28' integral with plate 28 to arrest the type wheel as will more fully hereinafter appear. A spacing sleeve 50 abuts against arm 49 and surrounds shaft 48 extending through bearing 46. Slidably keyed to shaft 48 are the friction clutch plates 51 the lower one of which abuts against the upper end of sleeve 50. Disks 52 of friction material are disposed between plates 51 and worm wheel 53 which is rotatably mounted on shaft 48. Worm wheel 53 meshes with and is driven by a worm 54 which is slidably keyed to and driven by shaft 55. Shaft 55 is continuously driven from the continuously operating printer drive motor through a suitable gear chain (not shown) and extends through and is journaled in the housing section 56 of the frame 45. Worm 54 is positioned between suitable abutments of the housing section 56 and is moved along shaft 55 with the frame and parts in the operation of the device. Formed integrally with frame 45 are supporting extensions 57 on which the supporting rollers 58 are rotatably secured by means of the pins 59.

Shaft 48 is provided with a collar 61 and interposed between this collar and the upper clutch disk 51 is the helical spring 62 which urges the type wheel shaft 48 upward until the upper face of collar 61 engages the lower face of bearing 47, and at the same time compresses the friction clutch parts for driving shaft 48. Supported on the upper end of shaft 48 by means of the threaded extension 63 and nut 64 is type supporting wheel structure 65 which is provided with downwardly extending spacing sections 66. Supported in the lower part of spacing sections 66 is the pivot ring 67 over which the lower ends of the type carrying elements or bars 68 are hooked. Bars 68 are spaced apart by the projections 66, and are held in normal substantially vertical position by means of springs 69 individual to the type bars and secured to the lower ends of extensions 66 by means of the screws 70. One bar 68 is preferably provided for each selective combination of notches that may be set up on the selector disks 10 to 14 inclusive. Each of the bars 68 is provided with a centering and striking projection 71 adapted to be brought into substantial alignment with the V-shaped end 72 (Figures 5 and 6) of the striking lever or arm 73. Arm 73 is pivotally supported for alignment with the printing position of a selected type bar by means of the pin 74 from the carriage framework 45 and the lower end 75

thereof is normally positioned in the path of movement of the striking bail 76. Bail 76 is carried on an arm 77 which in turn is secured to the actuating rod 78. Each time the arm 49 engages a selected latch 20 arresting the type wheel mechanism, rod 78 is actuated by a mechanism (not shown) preferably operated from a cam carried on printer main shaft 33 to effect a printing stroke of the striking bail 76 which may be effected by resilient means if desired.

As shown, twenty-six type bars 68 are provided and each bar is provided with a lower case and an upper case character indicated by the numerals 79 and 80 respectively. Supported from frame 45 and yieldingly pressed against the character elements 79 and 80 by means of spring 81 is an inking roller 82 which may be of any well known or standard construction. Disposed opposite the inking roller 82 and adjacent the position of the striker arm 73 is a suitable platen 83 mounted on platen carrying shaft 84. It will be understood that platen 83 is provided with suitable paper guiding means (not shown) by means of which the paper upon which the characters are to be printed is held in proper position to receive the printing impact of the selected characters. Suitable line feed and shifting mechanisms (not shown) are also provided for the platen which may be of any well known construction. Various types of such mechanisms are well known to those skilled in the art and form no part of the present invention. These mechanisms for effecting the paging or function operations are controlled independently of the character selecting disks 10 to 14 by the vanes 1 to 5 through the function control bars 86. Function control bars 86 are provided with suitable notches arranged to permit the bars to drop in well known manner upon the setting of the selector vanes in the various combinations allotted to the individual bars. The notches in the character selector disks 10 to 14 and in the bars 86 may be so arranged that when one of the bars 86 is permitted to drop, none of the latches 20 will be selected by the bars 10 to 14 and the control mechanism for shaft 33 is preferably arranged so that when a bar 86 is selected the shaft 33 will not be released for rotation. When so arranged during function or paging operations, shaft 33 will remain at rest and no printing operation will occur. It will be obvious to those skilled in the art that one or more control operations may simultaneously be performed by the bars 86, as for example the line feed and carriage return control bars 86 may be simultaneously selected.

At the beginning of a cycle of operations shaft 33 is stationary with the high part of cam 31 under roller 29 and plate 28 is raised holding latches 20 out of engagement with permutation disks 10 to 14. When no sig-

nals are being received pin 28' is engaged by arm 49 arresting the rotation of the type-wheel. When a code combination of character selecting conditions is received, vanes 1 to 5 are tilted in accordance with the marking and spacing conditions received. Tilting of the vanes rotates the disks 10 to 14 inclusive individual thereto to the right or left as the case may be, and upon or after receipt of the last selecting condition of the code combination shaft 33 is started into rotation and cam 31 is rotated permitting plate 28 to drop disengaging pin 28' from arm 49 freeing the type wheel for rotation, and permitting latches 20 to shift into engagement with disks 10 to 14. A set of notches on disks 10 to 14 corresponding to the received code combination is lined up under one latch 20 and the latch adjacent the aligned slots will shift inward into the aligned slots about its pivot point under the influence of the spring 25 individual thereto into the path of rotation of arm 49. The remaining latches 20 will engage one or more of the projections of disks 10 to 14 and will be held out of the path of movement of the rotating arm 49. Type wheel shaft 49 is normally driven at such a speed that before the roller 30 of the restoring plate 28 begins to ride up on the high part of the cam 31 towards the end of the revolution of shaft 33 the outer end of arm 49 will engage the selected latch 20 and the type wheel will be brought to rest with the selected character in printing position, regardless of the location of the selected latch about the periphery of the selecting disks 10 to 14. Immediately after arm 49 engages the selected latch and just before plate 28 is raised by the high part of the cam 31 to restore the latches to unactuated position, shaft 78 is rocked, striking bail 76 against the extension 75 of the printing arm 73 and causing the V-shaped end 72 thereof to engage the centering and striking projections 71 of the selected type carrying bar 68. This centers the selected type bar and causes a printing impact of the selected character against the paper supported by the platen 83. Immediately after the printing impact of the selected type bar, plate 28 engages extension 27 of the selected latch 20 and shifts it out of the aligned notches. All of the latches 20 are forced out of engagement with the disks 10 to 14 and shaft 33 comes to rest completing the cycle of operations and conditioning the mechanism for the succeeding cycle of operations. During each rotation of shaft 33 the worm 34 is rotated through a single revolution and shifts the frame 45 together with the mechanism carried thereby a distance of one space with relation to the stationary platen 83 to effect proper spacing between printed characters. This cycle of operations is repeated for each code combination of character selecting conditions received. As soon as selector latches 130

20 are restored a succeeding combination may be set up on the disks 10 to 14. By providing a suitable receiving mechanism interposed between the line and the control members 8, the reception of a succeeding code combination may proceed during the printing of the preceding selected character. In this manner an overlap of the printing and receiving operations may be provided.

10 The mechanism as shown is in position for the printing of a lower case character 79. When it is desired to print an upper case character 80 a shift control code combination must be transmitted causing selecting of the shift control bar 86, and operation of the shift mechanism to raise the platen 83 so that the upper case character 80 of the selected type bar will be in position to deliver a printing impact to the paper. The character selecting combination must then be transmitted and the upper case character of the selected type bar will be printed. Before another lower case character can be printed, a special unshift code combination must be received to cause selection of the unshift control bar 86 to restore platen 83 to its lower case position. At the completion of a line a special code combination is transmitted to actuate line feed control bar 86 effecting rotation of the platen a distance of one line. To effect the carriage return a code combination is transmitted to select the carriage return control bar 86 causing actuation of the carriage return bar 43 and rotation of arm 38 and rack 37 in a counter-clockwise direction, disengaging the rack 37 from the worm 34. A carriage return mechanism of any well known type (not shown) restores the carriage to its starting position at the beginning 40 of the line. A plurality of bars 86 may be simultaneously selected, and it is to be noted that during the function operations, shaft 33 remains stationary holding plate 28 upward with pin 28' in the path of rotation of arm 49. Arm 49 will accordingly engage pin 28' arresting the type wheel, and no spacing or printing operation will occur when a function is selected.

50 While the mechanism has been described in connection with a page printer having a movable type carrying carriage, it will be understood by those skilled in the art that it may be utilized in a printer in which the paper platen is movable to effect character spacing.

55 Also, instead of shifting the platen to effect printing of upper case characters the type carrying wheel or basket may be shifted vertically to effect the shift operation. If desired, the shift mechanism may be entirely eliminated, and the number of character elements and permutation disks may be increased to effect the printing of any desired number of characters. The invention is also adapted for use as a tape printer by making the carriage stationary and providing a tape

feeding platen, or type wheel shaft 48 may be arranged in a substantially horizontal position and the tape may be fed by a suitable mechanism from right to left in a substantially horizontal plane across the front of the machine in a manner well known in the art. A solid type wheel upon which the type elements are rigidly secured may be also provided and a movable printing platen may be provided to impact the paper upon which the record is to be made against the type. Further variations without departing from the spirit of my invention will suggest themselves to those skilled in the art.

Accordingly, having described preferred embodiments only of my invention, what is desired to be secured by Letters Patent and claimed as new is:

1. In a printing telegraph receiver, a stationary paper platen, a plurality of selecting members, a plurality of latch members selectively operated by said selecting members, a plurality of type bar members individual to and controlled by said latch members, and a movable carriage for supporting all of said members.

2. In a printing telegraph receiver, a stationary paper platen, a carriage arranged to move transversely with respect to said platen, a plurality of type bar members, notched selector members operated to various combinations of positions in response to line impulses, a plurality of latch members individual to said type bars, and responsive to a predetermined setting of said notched members for selecting one of said type bars for operation, all of said members being supported on said carriage.

3. In a printing telegraph receiver, a stationary platen, a plurality of selecting members, a plurality of latch members selectively operated by said selecting members, a plurality of type members individual to and controlled by said latch members and a movable carriage for carrying all of said members, all of said members being movable parallel with respect to said platen.

4. In a printing telegraph receiver, a stationary platen, a plurality of selecting members, a plurality of type bars, a plurality of intermediate members, selecting mechanism for selectively operating said intermediate members, whereby one of said type bars is selected for operation, and a movable carriage for carrying all of said members.

5. In a printing telegraph receiver, a stationary paper platen, a plurality of notched selecting members, a plurality of latch members selectively operated by said selecting members, a plurality of type members individual to and controlled by said latch members, and a movable carriage for carrying all of said members, all of said members moving parallel with respect to said platen.

6. In a printing telegraph receiver, a sta-

- tionary paper platen, a plurality of notched selecting members, a plurality of latch members selectively operated by said selecting members, a plurality of type members individual to and controlled by said latch members, and a movable carriage for carrying all of said members, all of said members moving parallel with respect to said platen. 7. In a printing telegraph receiver, a stationary platen, a type wheel, a plurality of type bars arranged about the periphery of said type wheel and supported thereby, a plurality of selector members, a plurality of latch members individual to said type bars, said latch members being arranged to be selectively operated by predetermined settings of said selector members for bringing said type wheel to a stopped position at a predetermined point, all of said members being supported on said carriage. 8. In a printing telegraph receiver, a stationary platen, a type wheel, and a plurality of type bars arranged about the periphery of said type wheel, said type wheel being arranged to move parallel with respect to said platen. 9. In a printing telegraph receiver, a stationary platen, a movable type wheel, a plurality of type bars arranged about the periphery of said type wheel, and movable selector members for selecting said type bars for operation, said selector members moving with said type wheel. 10. In a printing telegraph receiver, the combination with a stationary platen, of a traveling carriage comprising a plurality of type bars arranged in a circle, a plurality of operable code bars, and electro-responsive selecting mechanism controlled by line current impulses and cooperating with said code bars for controlling the operation of said type bars. 11. In a printing telegraph receiver, a stationary paper platen, a plurality of type bars, and selector mechanism movable transversely with respect to said platen for selectively operating said type bars. 12. In a printing telegraph receiver, a type wheel movable to effect character spacing comprising a plurality of type bars, a stationary paper platen, and mechanism responsive to predetermined groups of line impulses for selectively controlling the operation of said type bars. 13. In a printing telegraph receiver, a stationary paper platen, a rotatable type wheel comprising a plurality of type bars, and selector mechanism for selectively operating said type wheel for printing, said selector mechanism being movable parallel with respect to said platen. 14. In a line printing telegraph receiver, the combination with a stationary platen, of a carriage movable to effect letter spacing, a plurality of type bars supported by said carriage and arranged in a circle, and permutation means selectively controlled by line current impulses for controlling the operation of the type bars for printing. 15. In a line printing telegraph receiver, the combination with a stationary platen, of a rotatable type wheel comprising a plurality of type bars movable with respect to said platen to effect character spacing and permutation means selectively controlled by line current impulses for controlling said type bars for printing operation. 16. In a printing telegraph receiver, a stationary platen, a plurality of type bars, a shaft, a carriage supported on said shaft, said carriage comprising selector mechanism for selectively operating said type bars, and means whereby said carriage is moved along said shaft parallel with respect to said platen. 17. In a printing telegraph receiver, a stationary platen, a plurality of type bars, an intermittently driven shaft, and a carriage supported on said shaft, said carriage comprising selector mechanism for selectively operating said type bars and a worm mechanism on said shaft whereby said carriage is moved along said shaft parallel with respect to said platen. 18. In a printing telegraph receiver, a stationary platen, a plurality of type bars movable in a path parallel to said platen, selector mechanism for selecting said type bars, and an intermittently driven shaft, said shaft being released for rotation by said selecting mechanism at the end of said selection. 19. In a printing telegraph receiver, a rotatable type wheel, a plurality of selecting members for selectively operating said type wheel, a shaft, a carriage for carrying said selecting members and type wheel supported on said shaft, a spacing worm carried by said shaft, and a spacing rack meshing with said worm. 20. In a printing telegraph receiver, a type wheel, a plurality of selecting members for selectively operating said type wheel, a shaft, a carriage for carrying said selecting members and type wheel supported on said shaft, a worm carried by said shaft, a spacing rack meshing with said worm, and means following said selective operation for rotating said shaft. 21. In a printing telegraph receiver, a stationary platen, a carriage comprising a type wheel, a plurality of type bars arranged about the periphery of said type wheel and selecting means for selecting one of said type bars, a printing shaft, a worm carried by said shaft, a rack meshing with said worm, means for intermittently rotating said shaft, whereby said carriage is moved transversely with respect to said shaft, and means operative responsive to a predetermined combination of impulses for disconnecting said rack from said worm.

22. In a printing telegraph receiver, a plurality of latch members, each having an operating and a non-operating condition, means whereby said latch members are normally urged toward their operating positions, selector mechanism operative in response to current impulses for permitting one of said latch members to assume its operating position, a moving carriage for supporting all of said elements, a start-stop shaft for supporting said carriage, means responsive to said selection for starting said shaft into rotation, and means operative when said shaft has assumed a predetermined position for returning said latch member to its non-operating position.
23. In a printing telegraph receiver, a plurality of latch members having an operating and a non-operating position, selector members for selectively permitting said latch members to assume their operating position and a start-stop shaft member for returning said latch members to their non-operating position.
24. In a printing telegraph receiver, a stationary platen, a plurality of latch members having an operating and a non-operating position, selector members for selectively permitting said latch members to assume their operating position, a start-stop shaft for returning said latch members to their non-operating position, and a movable carriage for supporting all of said members.
25. In a printing telegraph receiver, a type wheel, means for rotating said type wheel, selectively controlled means for bringing said type wheel to a stop at predetermined positions, means for selectively controlling said last-mentioned means, a carriage for supporting all of said aforementioned elements, a shaft for supporting said carriage, means whereby said shaft is under the control of said selecting means, and means whereby said selectable means is under the control of said selecting means and said shaft.
26. In a printing telegraph receiver, a type wheel movable to effect character spacing, and a plurality of pivoted type bars arranged about the periphery of said type wheel, each of said type bars having a plurality of type carried thereon.
27. In a printing telegraph receiver, a type wheel movable to effect character spacing, and a plurality of type carrying elements, each of said type carrying elements secured pivotally to said type wheel, each of said type carrying elements carrying a plurality of type members.
28. In a printing telegraph receiver, a paper platen, a type wheel movable in a path parallel to said platen, a plurality of type bars pivotally secured about the periphery of said type wheel, means for selectively positioning one of said type bars before said paper platen, and means operative following

said positioning, for pressing said type bar against said platen.

29. In a printing telegraph receiver, a type supporting wheel, a plurality of type carrying bars arranged about the periphery of said type wheel, means whereby said wheel is rotated to a predetermined position for selecting one of said type bars for operation, and a striking lever for operating the selected type bars, said striking lever being arranged to simultaneously center said selected bar.

30. In a printing telegraph receiver, a type wheel, a plurality of type bars pivotally secured about the periphery of said type wheel, selectively operated means for selecting one of said type bars for operation, and means for simultaneously centering and rotating said type bar about its pivot.

31. In a printing telegraph receiver, a paper platen, a type wheel, a plurality of type bars pivotally secured about the periphery of said type wheel, means for selectively positioning one of said type bars before said paper platen, and means for simultaneously further positioning and pressing said type bar against said platen.

32. In a printing telegraph receiver, a pivotally secured type carrying element, a striking lever, and means whereby said striking lever rotates the type carrying element about said pivot and simultaneously moves it transversely with respect to said pivot.

33. In a printing telegraph receiver, a type wheel movable to effect character spacing, a plurality of type bars arranged about the periphery of said type wheel, each of said type bars being pivotally secured to said type wheel, means for rotating said type wheel to a predetermined position for selecting one of said type bars for operation, and means operative following said selection for rotating said selected type bar about its pivot.

34. In a printing telegraph receiver, a type wheel, a plurality of type bars arranged about the periphery of said type wheel, and means whereby each of said type bars have at least two different rotary movements and a linear movement.

35. In a printing telegraph receiver, a type supporting wheel movable to effect character spacing, type carrying bars arranged about the periphery of said type wheel, spacing sections arranged about the periphery of said type wheel, and a striking lever arranged to operate said type carrying bars, the striking surface of said lever being of V-shape.

36. In a printing telegraph receiver, a plurality of vertically positioned setting vanes, and means for tilting said vanes from said vertical combinations in accordance with code combinations of received marking and spacing impulses.

37. In a printing telegraph receiver, a plurality of vertically positioned setting vanes provided with actuating extensions, and

means engaging said extensions and responsive to predetermined combinations of received impulses for tilting said vanes.

38. In a printing telegraph receiver, a plurality of vertically positioned setting vanes provided with actuating extensions, and vane setting members coacting with said extensions and responsive to predetermined combinations of impulses for tilting said vane members.

39. In a printing telegraph receiver, a plurality of setting vanes, each operative to a plurality of positions, and a notched selector member individual to each of said setting vanes and operable to a predetermined position thereby, said notched member being movable transversely with respect to said setting vanes.

40. In a printing telegraph receiver, the combination with a movable type carriage comprising a plurality of type bars, a stationary paper platen, and longitudinally pivoted mechanism responsive to predetermined groups of line current impulses for selectively controlling the operation of said type bars against said platen.

41. In a printing telegraph receiver, a movable type carriage comprising a plurality of type bars, a stationary paper platen, and longitudinally pivoted bars normally in a vertical position and arranged to be tilted to a slightly inclined vertical position responsive to predetermined groups of line current impulses for selectively controlling the operation of said type bars.

42. In a printing telegraph receiver, a traveling carriage having a plurality of selectable members movable therewith, said members being arcuately arranged, a plurality of stationary selectable members, and means common to all of said members for selecting any one of them.

43. In a printing telegraph receiver, a platen, a carriage movable with respect to said platen comprising rotatable members operable to a plurality of positions, members stationary with respect to said platen, and selector mechanism common to said rotatable members for selectively operating them.

44. In a printing telegraph receiver, a stationary paper platen, a plurality of movable type bars, said type bars being movable parallel with respect to said paper platen, a plurality of special operating members stationary with respect to said platen, and means responsive to predetermined groups of line current impulses and common to said special operating members and said type bars for selectively operating them.

45. In a printing telegraph receiver, a stationary paper platen, a plurality of type bars, selector mechanism operative in predetermined combinations for selectively operating said type bars, said selector mechanism being movable parallel with respect to said platen,

en, a plurality of special operating members, and selector mechanism operable in predetermined combinations for selectively operating said type bar selector mechanism and said special operating members.

46. In a printing telegraph receiver, a stationary paper platen, a plurality of type bars movable to effect character spacing, notched selector mechanism operable in predetermined combinations for selectively operating said type bars, other members for special operations, and control vanes common to said selector mechanism and said other members.

47. In a printing telegraph receiver, a stationary paper platen, a plurality of type bars, notched selector mechanism for selectively operating said type bars, a movable carriage member for supporting said selector mechanism and said type bars, a plurality of stunt members, and operating vanes common to said selectors and said other members and responsive to predetermined combinations of current impulses.

48. In a printing telegraph receiver, a platen, a type wheel shaft movable to effect character spacing, a type supporting wheel on said shaft, type bars arranged about the periphery of said shaft, each of said type bars having an upper and lower case shift, means for pivotally supporting said type bars, said type bars being normally held in a vertical position, and a striking bail for operating said type bars about their pivot against said platen.

49. In a printing telegraph receiver, a type supporting wheel movable to effect character spacing, type carrying bars arranged about the periphery of said type supporting wheel, means for normally maintaining said type carrying bars in a vertical position, and means whereby said type carrying bars may be tilted from said vertical position.

50. In a printing telegraph receiver, a plurality of type bars, setting vanes provided at their ends with vane pivots, means responsive to predetermined combinations of line current impulses for longitudinally rocking said setting vanes about their vane pivots, notched character selecting disks operated by said setting vanes to selectively align the notches, and means responsive to the alignment of said notches for selecting one of said type bars for operation.

51. In a printing telegraph receiver, the combination with a plurality of type bars, selector bars, longitudinal pivots for said selector bars, means responsive to predetermined combinations of impulses for tilting said selector bars about said pivots, and means controlled by said tilting movement for selecting one of said type bars for operation.

52. In a printing telegraph receiver, a type wheel, a platen, means for moving said type wheel with respect to said platen, selector mechanism movable with said type-

wheel responsive to received code combinations of impulses for selectively operating said typewheel, and means for preventing rotation of said typewheel when no character selecting impulses are being received.

53. In a printing telegraph, a typewheel, a platen, means for moving said typewheel with respect to said platen, a plurality of stop devices normally urged into the path 10 of said typewheel for bringing said typewheel to a stop, selector mechanism for selectively releasing one of said stop devices to move into the path of said typewheel, a power shaft, and means controlled by said shaft for moving said stop devices out of the path of said selector mechanisms.

54. In a printing telegraph, a typewheel, a plurality of stop devices normally urged into the path of said typewheel, selector 20 mechanism normally holding said stop devices out of the path of said typewheel, said selector mechanism being responsive to received code combinations of impulses for permitting one of said stop devices to move 25 into the path of said typewheel, a power shaft, means controlled by said shaft for moving said stop device out of the path of said type wheel, and means controlled by said shaft for locking said typewheel from rotation.

55. In a printing telegraph, a typewheel normally rotating, a platen, means for moving said typewheel transversely with respect to said platen, means for selectively stopping said typewheel for printing operations, a power shaft, and means controlled by said shaft for locking said typewheel from rotation.

56. In a printing mechanism, a single magnet responsive to received code combinations 40 of impulse conditions, a stationary paper platen, a plurality of selectors variably operated by said magnet in accordance with the received code combinations, a carriage movable with respect to said platen for carrying a plurality of type bars, and means controlled by said selectors for selecting a type bar for printing its character.

57. In a printing mechanism, a single magnet responsive to received code combinations 50 of impulse conditions, a stationary paper platen, a plurality of selectors variably operated by said magnet in accordance with the received code combinations, a carriage carrying a plurality of type bars, means controlled by said selectors for selecting a type bar for printing its character, and means for moving said carriage with respect to said platen.

58. In a printing telegraph, a single magnet responsive to received code combinations 60 of impulse conditions, a plurality of type bars, a plurality of selecting members for selectively operating said type bars, a shaft, a carriage for carrying said type characters

mounted on said shaft, a spacing worm carried by said shaft, and a spacing rack meshing with said worm.

59. In a printing telegraph, a single magnet responsive to received code combinations 70 of impulse conditions, a plurality of type bars, a plurality of selecting members for selectively operating said type bars, a stationary paper platen, a shaft, a carriage for carrying said type characters mounted on said shaft, a spacing worm carried by said shaft, and a spacing rack meshing with said worm whereby said type bars are moved with respect to said platen.

60. In a printing telegraph receiver, a stationary platen, a plurality of type bars, an intermittently driven shaft, a carriage for carrying said type bars mounted on said shaft, a single magnet responsive to received 80 code combinations of impulse conditions for selectively operating said type bars, and a worm mechanism on said shaft whereby said carriage is moved along said shaft transversely with respect to said platen.

61. In a printing telegraph receiver, a single magnet responsive to code combinations of impulse conditions, a stationary paper platen, a plurality of type bars, notched selector mechanism operable in predetermined combinations for selectively operating said type bars, other members for special operations, and control vanes common to said selector mechanism and said other members for operating said mechanism and members, said vanes being variably operated by said magnet.

62. In a printing telegraph receiver, a stationary paper platen, a plurality of type bars, notched selector mechanism for selectively operating said type bars, a movable carriage 105 member for supporting said selector mechanism and said type bars, a plurality of stunt members and operating vanes common to said selectors and said other members, and a single magnet responsive to predetermined combinations of current impulses for variably operating said vanes.

63. In a printing telegraph receiver, a stationary platen, a carriage movable with respect to said platen, a plurality of type bars supported on said carriage, each of said type bars having an upper and lower case shift, means for pivotally supporting said type bars, said type bars being normally held in a vertical position, a single magnet responsive to received code combinations of impulse conditions for selecting a type bar, a striking bail for operating said type bars about their pivot against said platen, and means for moving said carriage with respect to said platen.

64. In a printing mechanism, a single magnet responsive to received code combinations of impulse conditions, a stationary paper platen, a plurality of selectors variably operated by said magnet in accordance with the 130

received code combinations, a carriage carrying a plurality of type bars, means controlled by said selectors for selecting a type bar for printing its character, and means controlled by said magnet for moving said carriage with respect to said platen.

65. In a printing telegraph receiver, a stationary paper platen, a plurality of type bars, notched selector mechanism for selectively operating said type bars, a movable carriage member for supporting said selector mechanism and said type bars, a plurality of stunt members and operating vanes common to said selectors and said other members, and a single magnet responsive to predetermined combinations of current impulses for variably operating said vanes and for controlling said carriage.

66. In a printing telegraph receiver, a stationary platen, a carriage movable with respect to said platen, a plurality of type bars supported on said carriage, each of said type bars having an upper and lower case shift, means for pivotally supporting said type bars, said type bars being normally held in a vertical position, a single magnet responsive to received code combinations of impulse conditions for selecting a type bar, a striking bail for operating said type bars about their pivot against said platen, and means controlled by said magnet for moving said carriage with respect to said platen.

67. In a recorder, a stationary paper platen, a type carriage movable to form character spaces, permutation code mechanism mounted on said carriage, and means to operate the permutation mechanism according to the record to be made.

68. In a recorder, a stationary paper platen, a type carriage movable to form character spaces, means to perform recorder control functions other than recording, a permutation device movable with the carriage to determine the character to be recorded, and a permutation device in the stationary part of the machine to control the functions.

69. In a recorder, a type carriage movable to form character spaces, and an intermittently operable striking bail mounted on said carriage and adapted to perform the recording operation.

70. In a recorder, a type carriage movable to form character spaces, means to perform recorder control functions other than recording, a permutation device movable with the carriage to determine the character to be recorded, a permutation device in the stationary part of the machine comprising a plurality of rockable selector vanes, and a plurality of function bars to engage said vanes in variant combinations to control said functions.

71. In a recorder, a stationary frame, a carriage movable to form character spaces, a plurality of type bars mounted on said carriage,

electro-responsive means on the stationary frame of the machine, and a connection entirely mechanical between said carriage and said electro-responsive means to select the type-bar to be operated.

70

72. In a recorder, a type carriage movable to form character spaces, an intermittently operable striking bail mounted on said carriage and adapted to perform the recording operation, driven means on the stationary part of the machine, and an operating connection between said driven means and said intermittently operable member.

75

73. In a recorder, a stationary frame, a recording member movable to form character spaces, means to perform functions other than recording, a permutation device movable with said recording member to selectively control said member, and a second permutation device mounted in the stationary frame to selectively control the functions.

80

74. In a printing telegraph receiver, a stationary frame, a movable type carriage having a plurality of type bars thereon, a plurality of tilttable vanes on the stationary frame, and mechanical means controlling the selection of said type bars by the positions of said tilting vanes.

85

75. In a recorder, a stationary paper platen, a type carriage movable to form character spaces, a typewheel mounted in said carriage, permutation code mechanism mounted in said carriage, means to position said type wheel under the control of said permutation code mechanism, and means to operate said permutation mechanism according to the record to be made.

90

76. In a printing telegraph receiver, a typewheel, selector mechanism for selectively controlling said typewheel, mechanism for operating said typewheel, means for performing receiver control operations independently of said typewheel operations, and separate operating mechanism for said means.

100

77. In a printing telegraph receiver, a paper platen, a movable typewheel, selector mechanism for selectively controlling said typewheel, mechanism for operating said typewheel, means for performing platen control operations, and mechanism independent of said first mentioned mechanism for operating said means.

110

78. In a printing telegraph receiver, a paper platen, a type carriage transversely movable with respect to said platen comprising a typewheel and selector mechanism for selectively controlling said typewheel, operating means for said selector mechanism and typewheel, a plurality of receiver control devices, means for selectively controlling said devices, and separate operating mechanism for said devices.

120

79. In a printing telegraph receiver, a stationary paper platen, a movable type car-

125

riage comprising a typewheel and selector mechanism for selectively controlling said typewheel, means for operating said selector mechanism, a plurality of platen and receiver control devices, means for selectively controlling the operation of said devices, and means independent of said first mentioned means for operating said second mentioned means.

5 80. In a printing telegraph receiver, a stationary platen, a typewheel, selector mechanism for selectively controlling the operation of said typewheel, control mechanisms for selectively controlling said platen, and different operating mechanisms for controlling 10 said typewheel and said control mechanisms.

15 81. In a printing telegraph receiver, a stationary platen, a typewheel, selector mechanism for selectively controlling the operation of said typewheel, said selector mechanism 20 and said typewheel being arranged to move transversely with respect to said platen, a plurality of members for performing receiver control operations, and different operating mechanisms for said selective control of said 25 typewheel and members.

82. In a telegraph receiver, a record receiving material, a plurality of individual recording members movable across said receiving material between succeeding recording 30 operations to form spaces between succeeding records, and a selector mechanism movable with said members across said receiving material comprising a plurality of relatively movable elements for selectively operating 35 said members.

83. In a printing telegraph receiver, a carriage movable to produce character spaces, a series of type carried by said carriage, a plurality of latch members mounted in said carriage, each having an operating and a non-operating position, means whereby said latch members are normally urged toward their operating positions, selector mechanism operative in response to current impulses for 40 permitting one of said latch members to assume its operating position, and means to record from said type under the control of said operated latch member.

84. In a printing telegraph receiver, a type 45 carrying member, a carrier for said type carrying member movable to form character spaces, a permutation selecting device mounted in said carrier, a series of elements greater in number than the number of elements in said permutation device, means to select one of said elements according to the setting of said permutation device, and means to record from said type carrying member according to the element operated.

85. In a printing telegraph receiver, a paper platen, a movable carriage, type bars mounted in said carriage, selector mechanism mounted in said carriage for selectively controlling said type bars, mechanism for operating said type bars, means for performing

platen control operations, and mechanism independent of said first mentioned mechanism for operating said means.

86. In a printing telegraph receiver, a stationary paper platen, a plurality of individual type bars, and selector mechanism operative to select one of a plurality of type bars, said type bars and said selector mechanism being movable parallel to said platen to effect spacing between recorded characters.

87. In a printing telegraph receiver, a stationary paper platen, a plurality of selecting members, a plurality of control members selectively operated by said selecting members, a plurality of type bar members individual to 80 and controlled by said control members, and a carriage movable substantially parallel to said platen for supporting all of said members.

88. In a recorder, a movable type carriage, 85 ink carrying means mounted on said carriage, and an intermittently operable member mounted on said carriage and adapted to perform the recording operations, said ink carrying means being arranged to provide visibility of the record as it is made.

89. In a recorder, a carriage movable to form character spaces, a plurality of selectable type bars mounted on said carriage, a single magnet having an armature, and entirely mechanical means interposed between said carriage and the armature of said magnet to select the type bars to be operated.

90. In a selecting mechanism, a plurality of selecting members capable of being moved to a plurality of positions, a plurality of elements selectively conditioned for operation by said selecting members, means for operating said elements, and means for locking said selecting members during operation 105 of said selected elements.

91. In a recorder, a plurality of character elements, a permutation mechanism comprising a plurality of movable selector members operative to select the character element to be operated, means for operating the selected character element, and means to lock said movable selector members in position during the printing operation of said selected character element.

92. In a recorder, a paper platen, a plurality of type bars cooperating therewith, said carriage and platen being relatively movable to form character spaces, a permutation mechanism comprising a plurality of movable selector members to select the type bar to be operated, and means to lock said selector members in position during the printing operation.

93. In a recorder, a plurality of character elements, a permutation mechanism comprising a plurality of tiltable selector vanes to select the character element to be operated, printing means to operate the character element, and means to lock said tilting vanes.

during the printing operation of said printing means.

94. In a recorder, a recording member movable to form character spaces, means to perform function other than recording, a permutation device movable with said recording member to selectively control said member comprising a plurality of selectable members, and a second permutation device mounted to selectively control recorder function operations.

95. In a printing telegraph receiver, a plurality of type bars arranged in a circle, a plurality of notched selecting disks positioned horizontally and below said type bars, means for operating said disks in a horizontal plane to select one of said type bars for operation, and means responsive following the selection for operating the selected type bar to record the character carried thereby.

96. In a printing telegraph receiver, a vertically extending support, a plurality of selecting members supported in different horizontal planes by said support, a plurality of type bars arranged in a circle and positioned directly above said members, means for moving said members in their respective horizontal planes to select a type bar, and means responsive following the selection for operating the selected type bar to record the character carried thereby.

97. In a printing telegraph receiver, a circular type basket, a plurality of type bars positioned vertically in said basket, a plurality of selector disks positioned in a horizontal plane below said type basket, means for operating said disks to select one of said type bars, and means operated following the selection of the type bar for effecting its operation.

98. In a printing telegraph receiver, a support, a plurality of selecting members held in different horizontal planes by said support, a plurality of type bars arranged in a circle and positioned directly above said members, a plurality of latch members, each having an operating and a non-operating position, means whereby said latch members are normally urged toward their operating position, said selecting members operative in response to current impulses for permitting one of said latch members to assume its operating position, and means to record from said type bars under the control of said operated latch member.

In testimony whereof I affix my signature.
STERLING MORTON.
